UNITED STATES PATENT OFFICE

NEWTON J. SHEKERJIAN, OF NEW YORK, N. Y.

PLIERS

Application filed August 17, 1931. Serial No. 557,691.

This invention relates to an improved pair of pliers having pivoted jaws which is intended especially for fine work such as in cabinet making, furniture repairing, uphol-
5 stering and the like.

A primary object of this invention is to enable the pivoted jaws to efficiently remove nails, tacks, brads, screws, staples and the like from furniture or other woodwork, so
10 that the woodwork is not marred or blemished as generally occurs in dislodging the same by means of pincers, pliers or prying implements as heretofore used.

A further object of this invention is to
15 provide a pivoted jaw tool with supplementary pulling lips or jaws which are of smaller size than the main jaws and which are adjustable in relation thereto to a very fine degree.

20 A further object of this invention is to provide an improved adjusting and securing means for the jaws, whereby the jaws may be quickly and easily either secured or adjusted in position to compensate for shortening
25 of the jaws as they are sharpened after being worn and to allow the jaws to be adjusted relative to the main jaws.

Still another object of this invention is to
30 provide one of the permanent jaws with a removable or integral fulcrum member, whereby a greater pulling leverage may be exerted on the jaws without marring or injuring the object from which the nail or other member is being removed.

35 Yet another object of this invention is to provide a pair of removable adjustable cutters on the permanent jaws which are capable of being quickly removed for resharpen-
40 ing or replacing and of being easily secured and adjusted while in position.

With the foregoing and other objects in view as will hereinafter become apparent, this invention comprises the constructions,
45 combinations and arrangements of parts, hereinafter set forth, claimed and shown on the accompanying drawing.

In the drawing,

50 Figure 1 is a plan view of the pliers con-
stituting this invention.

Figure 2 is a side view of Figure 1 looking from the right hand side thereof.

Figure 3 is a plan view of the head of the pliers.

Figure 4 is a plan view looking down at
55 the top end of Figure 1.

Figure 5 is a perspective view of the jaw having the removable fulcrum member thereon.

Figure 6 is a cross section on line 6-6
60 of Figure 3 through removable jaw securing means, and

Figure 7 is a section on line 7-7 of Figure 6.

The combination tool constituting this invention includes a pair of arched handle members 10 and 11, pivoted to each other as at 12 and merging into opposed permanent or integral jaws 13 and 14, the meeting portion of the handle 10 and 11 being recessed at
65 the pivoted point as shown at 15 and 16.

Each of the integral jaws 13 and 14 has a cooperating adjustable removable jaw 17 and 18 therein, and inasmuch as the construction
70 of each of these jaws 17 and 18 and their securing means 20 is identical, only one of them needs to be described in detail. Each jaw 17 and 18 is provided with a gripping point 19
75 cooperating with a similar gripping point of the opposing jaw. A pair of opposite longitudinal channels 21 and 22 are provided on opposite sides of the removable jaw member, while the back of the removable jaw member is provided with ratchet teeth 23. The permanent jaw members 13 and 14 are each provided with a longitudinal channel 24 from opposite sides of which project a pair of longitudinal ribs 25 and 26. The channel 24 is of
80 such a size and length as to snugly receive the removable jaw 17 or 18 therein, with the channel members 21 and 22 cooperating with the ribs 25 and 26, thereby allowing the jaw members 17 or 18 to move freely longitudinally, but not transversely to the permanent jaw members. The channel 24 will be deep
85 enough to allow the teeth 23 to move freely therein without coming in contact with the permanent jaw member.

Recessed within the permanent jaw member from the channel 24 is a well 27 adapted
90
95
100

to receive therein a tooth plug 28 and leading to this well 27 is a threaded opening through which a screw member 29 may pass and place the plug member 28 into mesh with the teeth 23 of jaw 17 or 18. The head 30 of screw member 29 is countersunk in an exterior well 31 of the permanent jaw. When the screw member 29 is tightened, it will force the tooth plug 28 against the teeth 23 of jaw 17 or 18, holding it immovably in position. To remove the jaws, the screw member 29 is withdrawn, thereby allowing the tooth plug 28 to retract and the jaws 17 and 18 to be easily adjusted or removed. Due to the number of teeth 23 it is obvious that the points 19 may be set at any desired distance from the end of the permanent jaws.

Secured near the ends of the permanent jaws 13 and 14, which it will be noted are spaced apart, are a pair of cutters 32. Each cutter is longitudinally slotted as at 33 to provide for the passage of a screw 34 therethrough into a threaded opening 35 in the permanent jaw members, the cutter members having their sharpened ends 36 cooperating with each other.

Formed on one of the jaw members 14 is a fulcrum member 37 arcuately shaped as clearly shown in Figures 1, 3 and 5. This fulcrum member 37 projects slightly beyond the end of the jaw member of the integral jaw 13 as at 38 and may be either permanently or removably secured to the jaw member 14. In order to be removably secured, its contacting surface is made complementary to the outside edge of jaw 14 and the screw member 29 may also serve to secure fulcrum member 37 to jaw 14.

In operation, the jaw points 19 will be adjusted so as to project just the right amount beyond the ends of the permanent jaws for allowing them to grip the nail, brad or other tack or element that it is desired to extract.

The point 19 will enable the jaws to secure good grip on this element while the surface 38 of fulcrum 37 comes into contact with the piece of furniture or other object from which the element is being extracted. The pliers are then rotated about the arcuate surface 38 as a fulcrum point, thus providing a great deal of leverage with a minimum amount of effort and easy extraction of the element being removed results.

As will be observed, the pointed ends 19 of the removable jaws are comparatively small and thus occupy very little more space than the average small nail or brad being withdrawn so that there is no marring of the furniture being operated upon. The jaws 19 will grip the nail or brad securely without marring the wood.

When the points 19 become worn the jaws 17 and 18 may be easily removed by loosening screws 29 and resharpened and replaced,

the teeth 23 and tooth plug 28 allowing for adjusting the jaws as they are worn down by resharpening. Furthermore, the jaws may also be adjusted for the purpose of getting a deeper grip on the nail or brad being withdrawn when such is necessary. 70

The cutters 32 are operated by merely opening and closing the handles 10 and 11, and when worn may be easily removed by removing the screws 34 whereby the points 36 may be resharpened, the slots 33 allowing the jaws to be adjusted as the edges 36 are worn away through sharpening. 75

It will be noted that arched handles 10 and 11 have internal projections 39 and 40 which meet when the pliers are closed to limit the amount that the points 19 of the adjustable jaw 17 and 18 can approach each other. 80

In operation, it will be usually found desirable to so adjust the position of removable jaws 17 and 18 so that the points 19 thereof will just fail to come into contact or will be very slightly spaced apart at the time that projections 39 and 40 come into contact with each other and prevent the points 19 from clashing with each other. This will have the effect of lengthening the life of the points 19 in that there will be no wear of one point 19 against the opposite point 19. 85

The novel features and the operation of this device will be apparent from the foregoing description. While the device has been shown and the structure described in detail, it is obvious that this is not to be considered limited to the exact form disclosed and that changes may be made therein within the scope of what is claimed without departing from the spirit of the invention. 90

It is further to be understood that the cutters 32 each have its inner contact faces provided with a series of teeth (similar to the ratchet teeth 23 shown in detail of Figure 7) so that said cutters will be relatively immovable when in mesh with complementary ratchet teeth fixed upon the jaws 13 and 14 respectively. 105

Having thus set forth and disclosed the nature of this invention, what is claimed is: 110

1. In a pivoted jaw tool in combination a pair of pivoted handle members having integral opposing jaws, the opposing surface of each of said jaws having longitudinal channels therein, longitudinal rib members projecting from the opposite sides of said channels, removable jaw members receivable in said longitudinal channels, said removable jaw members having channels formed on opposite sides thereof to cooperate with said rib members, means cooperating with the backs of said removable jaw members to hold the same securely in adjustable positions, said means comprising a series of teeth formed on the back of the jaw members, a tooth block 115

received in a well in said integral jaw members, and means for holding said tooth block against the teeth of said removable jaw to lock said removable jaw in position.

5 2. In a pivoted jaw tool in combination a pair of pivoted handle members having integral opposing jaws, the opposing surface of each of said jaws having longitudinal channels therein, longitudinal rib members projecting from the opposite sides of said channels, removable jaw members receivable in said longitudinal channels, said removable jaw members having channels formed on opposite sides thereof to cooperate with said rib members, means cooperating with the backs of said removable jaw members to hold the same securely in adjustable positions, said means comprising a series of teeth formed on the back of the jaw members, a tooth block received in a well in said integral jaw members, and means for holding said tooth block against the teeth of said removable jaw to lock said removable jaw in position, said latter means comprising a screw member projecting through said integral jaw, said screw member being countersunk in said integral jaw.

In testimony whereof I affix my signature.

NEWTON J. SHEKERJIAN.
